CLAIM

I claim the ornamental design for a storage container, as shown and described.

DESCRIPTION

FIG. 1 shows an isometric view of a storage container.

FIG. 2 shows a front side elevation view of the storage container of FIG. 1.

FIG. 3 shows a rear side elevation view of the storage container of FIG. 1.

FIG. 4 shows a right side elevation view of the storage container of FIG. 1.

FIG. 5 shows a left side elevation view of the storage container of FIG. 1.

FIG. 6 shows a top view of the storage container of FIG. 1; and,

FIG. 7 shows a bottom view of the storage container of FIG. 1.

The even broken lines illustrate portions of the storage container that form no part of the claimed design. The dash dot broken lines represent boundaries of the claim and form no part of the claimed design.

1 Claim, 6 Drawing Sheets
